SIGNAL FLARE

John A. Gearon and Edward Gearon, Chicago, Ill.

Application November 16, 1948, Serial No. 60,232

6 Claims. (Cl. 102—37.4)

1

Our invention relates to signal flares of the type used by trainmen to warn succeeding traffic of an emergency or the necessity for a stop. Flares are carried as equipment on all trains and, when it is necessary, the trainman of the leading train lights and throws a flare some distance behind his train to serve as a signal for the succeeding train. A flare of the type under consideration is known as a fusee and has a tip like that of a safety match. The fusee carries a cap which is removable and reversible for application to the said tip, the cap having an abrasive substance suitable for lighting the tip when rubbed across the same.

Commonly, the intent is to throw the flare on the same track or close alongside. However, the flare often hits a rail or tie and bounces off to an adjoining or more distant track, where its presence may cause the stoppage of the wrong train, while failing to serve as a signal for the proper train. Another circumstance is that the flare may land on its tip with sufficient force to extinguish its flame. In both cases the signal fails, and an accident may occur.

In view of the above situation, it is one object of the present invention to provide an improved flare which contains means for ballasting or settling it where it may land in a position more or less free insofar as its burning is concerned.

A further object is to employ a material for weighting the flare which does not have a rebounding or bouncing tendency, whereby to permit the flare to remain where it hits or lands.

Another object is to provide a flare which contains means to form a spreading base when it hits or lands on an object or the surface of the ground, whereby to improve its stability and operative position.

An additional object is to include means in the novel flare to space its burning tip from the object or ground surface where it may land, so that the tendency for its flame to become extinguished is greatly reduced or eliminated.

An important object is to design the novel flare with few parts and along lines of simplicity, in order that it may be economically produced and handled with ease.

With the above objects in view, and any others which may suggest themselves from the description to follow, a better understanding of the invention may be had by reference to the accompanying drawing, in which—

Fig. 1 is a front elevation of the flare before it is prepared for use;

Fig. 2 is a vertical sectional view;

2

Fig. 3 is a side view of the flare in the form of use;

Fig. 4 is a top plan view; and

Fig. 5 is a section on the line 5—5 of Fig. 2, showing the flare in the settled and operative position.

In accordance with the foregoing, specific reference to the drawing indicates the basic feature of the flare to be a fusee 10, the firing tip of the same being shown at 11. The cap 12 is shown mounted on the fusee, the outer end of the cap having an abrasive coating 13 suitable to light the tip 11 when the cap is inverted and rubbed across the same. A tape 14 projects from the cap 12 for facility in pulling the same off the fusee.

For the purpose of the present invention the fusee 10 is designed to be packed in a bag 20 of paper or like material, Fig. 2 showing that the fusee is positioned in one side of the bag which 20 forms a pocket for the fusee. The lower portion of the bag is then filled with sand as shown at 21, or with any other material which is of a flowing nature and heavy weight.

The bag 20 is formed around its mouth with a 25 stiff band 25 of pasteboard or like material in a manner to reinforce the mouth of the bag. The bag also has a bottom reinforcement in the form of a band 26 of a material similar to that of the band 25. The bag is further formed in its front and rear walls with two rows of perforations 27, these being circular or elongated, as shown. The perforated areas of the bag are covered with vertical strips 28 of thin paper or like material.

The bag 20 carries a gummed tape 30 at the 35 side opposite from the one in which the fusee 10 is contained, as shown in Fig. 1. To prepare the flare in readiness for use it is rolled from the side in which the fusee is contained to become wrapped around itself, after which the tape 30 is moistened and tightly coiled around the package to bind it in the center.

The flare now appears as in Figs. 3 and 4, and it 45 will hold its vertical position when stored because of its bottom weight; and its sand filling will not spill because of the tight central binding of the bag. When the flare is to be used, the trainman simply reaches into its open top, pulls on the tape 14 to remove the fusee cap 12, lights the fusee in the usual manner and throws the flare in the desired direction. It follows that the flare will most likely land on its weighted end or bottom; or, should it land on a slant, the yielding of its sand content will adapt it to the surface where it lands in order to keep it in place. In either case, the soft filling of the flare will prevent it from

bouncing, so that the trainman may feel assured that the flare has landed on his own track.

In case the lighted end of the flare meets an obstacle, the reinforcing band 25 will keep the burning tip of its fuse amply spaced to enable it to continue burning, so that the top portion of the bag may also become lighted to improve the visibility of the fusee. Since the flare lands with a forcible impact, the expansive tendency of its filling acts to burst the paper strips or patches 28 which cover the perforations 27 in the walls of the flare. The result is the seepage or outward flow of the sand from the flare in the manner indicated in Fig. 5, this action forming a widened base for the flare and helping it to settle or become anchored to the spot where it has landed.

While the novel flare may be kept or stored upright in a box or other handy place, it may be desirable to have it hung in a suitable place on the crossbar of a railway car. For this purpose it is preferable to have the bottom of the flare extended with a laminated pasteboard hook 31 which may be used to hang the flare as stated when the same is inverted. Since the flare is tightly bound at the center, possible seepage of sand from the same when hung up may be considered as negligible. When the flare is thrown to the ground the hook 31 folds under it.

In view of the foregoing functional features, it is apparent that the novel flare is an article which not only employs the standard or long established fusee as its basic train signal, but also augments the same with means to check the flare from bouncing or glancing off the proper track, means to maintain its flame in action, means to adapt the flare to the spot where it lands, and means for the flare to form its own base or foundation. All of these features combine to produce a flare which is highly efficient, reliable, economical to produce and easy to handle.

While we have described the invention along specific lines, various minor changes or refinements may be made therein without departing from its principle, and we reserve the right to employ all such changes and refinements as may come within the scope and spirit of the appended claims.

We claim:

1. In a flare thrown from railway cars, the combination with a fusee of a relatively wide bag

in which the fusee is secured in upstanding position, the sides of the bag adapted to be gathered in the middle region, a loose material contained in the lower portion of the bag, and means to fasten the gathered portion of the bag and confine the material in said lower portion.

2. The structure of claim 1, the fusee being positioned along one side of the bag.

3. The structure of claim 1, and means breakable by the striking impact of the flare to allow the escape of the material and the settling thereof around the flare to stabilize the same.

4. The structure of claim 1, and means breakable by the striking impact of the flare to allow the escape of the material and the settling thereof around the flare to stabilize the same, said lower portion having perforations, and said breakable means comprising patches of relatively thin material secured to said portion over said perforations.

5. The structure of claim 1, and means breakable by the striking impact of the flare to allow the escape of the material and the settling thereof around the flare to stabilize the same, said lower portion having vertical rows of perforations, and said breakable means comprising vertical strips of relatively thin material secured to said portion over said perforations.

6. The structure of claim 1, and means breakable by the striking impact of the flare to allow the escape of the material and the settling thereof around the flare to stabilize the same, the fusee being positioned at one side of the bag and said lower portion having perforations remote from said side, and said breakable means comprising patches of relatively thin material secured to said portion over said perforations.

JOHN A. GEARON.
